Term of patent 14 years

(Cl. D33—7)

To all whom it may concern:

Be it known that I, De Lois J. Burchard, a citizen of the United States, residing at Russellville, in the county of Pope and State of Arkansas, have invented a new, original, and ornamental Design for a Desk, of which the following is a specification, reference being had to the accompanying drawing, forming part thereof.

Figure 1 is a rear perspective view of a desk showing my new design as it appears from the left side, and

Figure 2 is another rear perspective view thereof as it appears from the right side.

The dominant characteristics of my design reside in the portions shown in the figures in full lines, the essential features thereof being the horseshoe-shaped inner wall and the substantially semi-circular shelf member.

The appearance of the desk below the shelf at

the end of the occupant's opening is conventionally plain.

I claim:

The ornamental design for a desk, as shown and described.
